UNITED STATES PATENT OFFICE.

JOHN W. FISHER, OF NEW PHILADELPHIA, OHIO, ASSIGNOR OF ONE-HALF
TO HENRY B. FISHER, OF SAME PLACE.

WASHING-MACHINE.

SPECIFICATION forming part of Letters Patent No. 634,812, dated October 10, 1899.

Application filed March 30, 1898. Serial No. 675,704. (No model.)

To all whom it may concern:

Be it known that I, JOHN W. FISHER, of New Philadelphia, in the county of Tuscarawas and State of Ohio, have invented a new and Improved Washing-Machine, of which the following is a full, clear, and exact description.

This invention is a washing-machine of that class in which a reservoir is provided with a corrugated interior surface and contains a rubber which swings over the bottom of the reservoir to wash the clothes.

This specification is the disclosure of one form of my invention, while the claims define the actual scope thereof.

Reference is to be had to the accompanying drawings, forming a part of this specification, in which similar characters of reference indicate corresponding parts in all the figures.

Figure 1 is a side elevation of the invention. Fig. 2 is a sectional view on the line 2 2 of Fig. 3. Fig. 3 is a sectional view on the line 3 3 of Fig. 1; and Fig. 4 is a fragmentary elevation of the invention, showing particularly the outlet-pipe thereof.

The reservoir or body of the machine is formed of galvanized sheet-iron and embodies vertical smooth sides 5 of semicircular form joined to a curved and corrugated bottom 6. The sides and bottom are held at their upper edges by a rigid rectangular frame formed of side bars 7 and end bars 8, the side bars projecting beyond the end bars to form handles whereby the machine may be manipulated. Each end bar 8 has one end of the bottom 6 clamped against it by an interior clamping-cleat 9, which cleat forms a part of the rigid frame aforesaid. Joined rigidly to the middle lower portion of each side bar 7 are two downwardly-diverging legs 10, said connection being effected by suitable fastening devices or housings 11. The four legs 10 are connected in transverse pairs by rods, (designated 12 and 13, respectively,) which pass through the respective legs and beneath the bottom 6, the rods being held rigidly to the bottom by means of casings 14, formed on said bottom, two of such casings being provided for each rod.

The reservoir is provided with an outlet for discharging its liquid contents, which, as

shown in Figs. 3 and 4, has a valve commanding it. The valve comprises a casing 15, with a discharge-nozzle 16, directed downward and having a valve-stem 17, around which a spring 18 is arranged to press the valve normally in place. The stem 17 is connected with a handle-bar 19, by which the stem 17 may be drawn out to unseat the valve and open the discharge. The adjacent end of the tie-rod 13 is extended beyond the respective leg 10 and has the free portion of the handle-bar 19 rested thereon. This projected end of the tie-rod 13 is provided with a shoulder 20 (shown in Fig. 4) to be engaged by the handle-bar 19, whereby to hold the handle-bar outward and keep the valve unseated, for the purposes of which engagement the handle-bar 19 is provided with a wear-plate 21.

The rear side bar 7 is provided adjacent to each end with an eye 22. These eyes respectively hold hooks 23, fast on the rear corners of the box-cover 24. The front of the box-cover 24 is provided with a spring-latch 25, which coacts with a stud 26, secured to the front side bar 7 of the frame. By these means the box-cover is mounted to swing on the frame as though hinged; but by disconnecting the hooks 23 from the eyes 22 the cover may be removed from the body 80 of the machine, as will be understood.

The end walls of the cover 24 bear on the respective clamping-cleats 9, as shown in Fig. 2, so as to effect a tight joint and an effective closure. The side walls of the cover 24 bear on the side bars 7 of the frame for a like purpose. The cover is capable of being thrown back to the position shown in dotted lines in Fig. 3, so that access may be had to the interior of the reservoir. In order to support the cover in such dotted position, the cover is provided at its rear side with a pivotally-mounted rod 27, the outward movement of which is limited by the downturned end 28 of a plate 29, secured to the rear of the cover, as shown in Fig. 3. The right-hand end of the bottom 6 is extended outward over the right-hand end bar 8 of the frame and is supported on a wedge-shaped block 30, which extends between the right-hand ends of the side bars 7 of the frame and is supported thereon. Bearing down on this extension of the bottom

6 is a rail 31 with a notched lower edge. The rail 31 is held rigidly on the extension of the bottom by means of U-bolts 32, which pass astride of the right-hand ends of the side bar 7.

57. The rail 31 serves also to hold the block 30 in place. This arrangement causes all of the water splashed out of the reservoir to be drained back into the reservoir and also provides a ledge on which soap and other articles may be placed. The rail 31, held by U-bolts, is also intended for attaching a clothes-wringer thereto used in wringing the suds out of the clothes as they are removed from the tub. In addition to these functions the 15 structure serves to brace and render rigid the frame. The frame is further braced by tie-rods 33, which run, respectively, through the end bars 8 and are engaged with the side bars 7.

20. A rubber is mounted to swing in the body or reservoir and is constructed of heads 34, provided each with a rigidly-attached bar 46, joined rigidly by cross-bars 35 and having curved lower edges whereto triangular cleats 36 are fastened, which cleats form the corrugated working surface of the rubber. The heads 34 are also braced by additional cross-bars 37, located at their ends. The handle 38 of the rubber is attached to the middle portions of the bars 35 and passes up vertically through a slot 39 in the top of the cover 24. The upper end of the handle is provided with a cross-arm 40, by which to operate it. The rubber is hung from the inner side walls 35 of the cover 24 by means of four links arranged in two pairs, being designated, respectively, 41 and 42. The links 41 swing on fixed pivots 43, and the links 42 are provided with slots 44, receiving, respectively, pivots 45, attached to the cover. One link 42 and

one link 41 are on each side of the machine, and the links at each side are pivoted at their lower ends to each other and to the upper ends of the respective bars 46. The bars 46 are attached rigidly to the end portions of the cross-bars 35 and project up slightly above the rubber. This mounts the rubber so that it may swing back and forth on a constant pivot or so that it may move vertically in addition to its swinging. When the cover is to be raised to the position shown by dotted lines in Fig. 3, the rubber is drawn up into the cover, as the dotted lines show, so that the rubber may clear the body portion of the device in the movement out of the same. The upward movement of the rubber is permitted by the slots 44 in the links 42.

Having thus described my invention, I claim as new and desire to secure by Letters Patent—

1. In a washing-machine, the combination of a body portion, a cover mounted on the body portion, links pivotally connected with the cover, and a rubber pivotally connected with the links, a number of the links being slotted to permit the rubber to be swung on a pivot, or to be moved up and down.

2. A washing-machine having a body portion provided with two side bars, a rail running between the side bars at one end of the body portion, U-bolts straddling the rail and straddling the adjacent side bars to hold the rail firmly in place, and a block supported on the side bars and having the rail bearing down thereon, whereby to hold the block in place.

JOHN W. FISHER.
